GAS BURNER

August Berning, Essen, Germany, assignor to
Robert Muller, Essen, Germany

Application January 22, 1936, Serial No. 60,258
In Germany August 20, 1934

6 Claims. (Cl. 158—118)

The production and supply of the required compressed or blowing air by means of mechanical devices for compressed air gas burners which are known up to the present time, such as compressors, and fans and such like is disadvantageous in that the compressors, and fans require—besides much space and a great amount of power—a motor or other driving mechanism. Furthermore, such devices are of complicated 10 design and all rotating and sliding parts are submitted to a continuous wear. A further disadvantage of these devices is to be found in the insufficient mixing of gas and air, whereby the different air and gas streamlines flow one beside 15 the other without mixing intensively.

By this invention, the arrangement of all rotating and sliding parts are made superfluous owing to the fact that the required air is admitted into the gas stream by a known electromagnetic diaphragm blowing apparatus. The air is, thereby fed to the gas stream, contradistinction to the fuel gas and air mixer which are known so far, not in a continuous powerful and constant stream but—according to this invention—periodically and divided in separate puffs 25 of air, according to the velocity of the pulsations, of the vibrating diaphragm.

By means of this interrupted supply of the air the air puffs are blown into the gas stream 30 respectively into the existing mixture in quick succession whereby they bring about a thorough whirling of the gas and air mixture.

The increase and decrease of the air velocity which results herefrom, also increases the intensity of the whirling. Instead of intermittently feeding the air, the gaseous fuel or both the air and the gaseous fuel may be intermittently fed.

The mixing of the gas with air or oxygen takes place in a known manner in a mixing chamber 35 which is formed by the gas inlet main into which the electromagnetic vibrating diaphragm blowing apparatus blows the air. The mixing chamber is built in such a way that it serves as buffer for the air pulsations in order to avoid a flickering flame.

A further feature of this invention consists of an air pipe leading to the mixing chamber which is provided at a suitable place with slots or holes through which the quantity of air to be fed is sucked into the vibrating diaphragm chamber. Still another feature of this invention is based on the fact that the quantity of the air required and thereby of the constituents of the 50 gas-air mixture is brought about by the regulation of the vibrations of the diaphragm.

On the accompanying drawing an example of a burner according to the invention is illustrated, Figure 1 shows a longitudinal section, taken on line I—I, Fig. 2,

Figure 2 shows a cross section through the 5 burner taken on line II—II, Fig. 1.

In a base *a* of the burner, an electromagnet *c* is fixed by means of screws. The electromagnet receives its current by an electric plug *d*. An oscillating magnetism is excited in the magnetic field *e* when the alternating circuit is shut, and which magnetism causes the diaphragm *f* to swing in a number of vibrations resulting from the frequency of the alternating current. Hereby, an air movement is caused in the diaphragm 15 chamber *g* in such a way that the fresh air is sucked into the diaphragm chamber *g* through opening *q* made in the air pipe *i*, and opening *h* made in the surrounding tube *t*, and is blown in puffs into the upper mixing chamber *k* through 20 the air pipe *i*. The gas which enters through the gas connecting tube *l* flows between the air pipe *i* and the surrounding tube *t* and the outer tube *r* into the upper mixing chamber *k* which is formed by the upper part of the tube *r* and produces here with the entering air a well whirled mixture which may be ignited at the upper opening *m* of a hood *n* put on the tube *r*.

Should the quantity of air which is to be fed and consequently the composition of the air-gas 30 mixture be changed, then a variation of the distance of the diaphragm from the magnetic field can be made by turning the base *a* by means of the thread *o*, whereby an alteration of the amplitude of the vibrations of diaphragm *f* is 35 arrived at. In this way, the quantities of the separate air particles may be adjusted so that an air-gas mixture which is in accordance with the respective conditions will be produced. The measurements of the mixing chamber *k* shown in 40 the drawing, have to be chosen in such a manner that the air-gas mixture existing herein, when the apparatus is in operation, serves as shock absorber. It serves also for the purpose of decreasing the energy of the separate air particles 45 avoiding hereby a flickering.

The opening *p* is provided for the ventilating and cooling of the magnet. The hood *n* is movable and serves in a known manner for the regulation of the mixing chamber *k*. Screw *s* is 50 adjustable and secures the base in its position after the amplitude of the vibrations of the diaphragm have been regulated.

I claim:—

1. In an air-gas burner, means for mixing 55

- fuel-gas and air consisting of a diaphragm and an electro-magnet adapted to be excited by alternating current, said diaphragm being continuously vibrated by the electro-magnet for bringing one of the two constituents into the other, a mixing chamber, an inlet therein for supplying fuel-gas, another inlet for supplying air, a diaphragm chamber one wall of which consisting of said diaphragm, the diaphragm chamber opening into one of said inlets.
2. In an air-gas burner, a mixing chamber, a diaphragm chamber containing a diaphragm electromagnetically vibrated by alternating current, a pipe connected with the diaphragm chamber terminating in the lower end of the mixing chamber the upper end of which is open, an inlet opening into the said pipe, and another inlet opening into the lower end of the mixing chamber.
3. In an air-gas burner, a mixing chamber, a diaphragm chamber containing a diaphragm electromagnetically vibrated by alternating current, a pipe connected with the diaphragm chamber terminating in the lower end of the mixing chamber the upper end of which is open,

lateral inlets opening into the said pipe for the air arranged between the mixing chamber and the diaphragm chamber, and another inlet for the fuel gas arranged in the lower end of the mixing chamber.

4. In an air-gas burner, means for mixing fuel gas and air consisting of an electromagnetic vibration diaphragm apparatus containing a diaphragm, an electromagnet and means for varying the distance between the diaphragm and the electromagnet.

5. In an air-gas burner, a hollow socket, an electromagnet, a diaphragm chamber, both arranged in the interior of the socket, a burner pipe, a cap for closing the socket at the upper side and centrally bearing the burner pipe.

6. In an air-gas burner, a hollow socket, an electromagnet, arranged in the interior of it, a threaded cap for the upper side of the socket, a diaphragm vibrated by the said electromagnet and connected to the lower side of the cap, and a burner pipe centrally fixed to the upper side of the cap.

AUGUST BERNING. 25
